UNITED STATES PATENT OFFICE

153,042

DESIGN FOR A METALWORKING TOOL

Fred A. Sennewald, Van Nuys, Calif.

Application September 23, 1947, Serial No. 141,549

Term of patent 14 years

(Cl. D54—13)

To all whom it may concern:

Be it known that I, Fred A. Sennewald, a citizen of the United States, residing at Van Nuys, in the county of Los Angeles and State of California, have invented a new, original, and ornamental Design for a Metal Working Tool, of which the following is a specification, reference being had to the accompanying drawing, forming part thereof.

Figure 1 is a perspective view of a metal working tool, showing my new design;

Figure 2 is a top plan view of the article illustrated in Figure 1; and

Figure 3 is a right end elevational view of the device illustrated in Figure 1.

I claim:

The ornamental design for a metal working tool, substantially as shown.

FRED A. SENNEWALD.
